UNITED STATES PATENT OFFICE.

JOSEPH N. NIELSEN, OF CHICAGO, ILLINOIS.

PRINTING PROCESS AND APPARATUS.

Application filed January 14, 1921. Serial No. 437,223.

This invention relates to a printing process and an apparatus therefor wherein use is made of separable characters for setting up matter.

Setting up matter in type has maintained itself in universal use on account of its adaptability. It has a serious disadvantage, however, in that every size of a character requires its own type. Another disadvantage lies in the laborious and difficult formation of arrangement of type for formulæ and the like, usually requiring special cuts. In addition, after setting up, the type must be carefully leveled and handled so that every character makes the right impression in printing.

While matter in plate form is not subject to the careful and tedious handling for printing, it requires an extensive series of operations, and the same amount of care and labor in the setting up of type as with type set up for direct printing. It does not then obviate the disadvantage residing in the separable type and the use of plates is restricted to occasions where several printing elements of the same matter are required.

The principal objects of my invention are to provide a process and apparatus wherein the advantages residing in separable type are retained, wherein special matter, illustrations and the like may be readily inserted, and wherein the tedious and careful handling to which type are subject is obviated.

In another aspect the invention contemplates as objects, a process and apparatus, providing a printing element in plate form, and obviating much of the manipulation which the preparation of such an element entails.

These and other objects will be apparent hereinafter.

The process consists essentially in using separable characters, arranging them in desired formation on a holding device, and photographing the assembled characters. Since the characters are photographed, they need not be raised or depressed from the surface, but may be drawn, printed or otherwise delineated on the surface. In addition, but one size is required, the change to a desired size being accomplished in the photographing.

The characters are preferably made in light color, on a dark background and the holding device is also made dark. By this means it is possible to photograph on a

sensitized element and prepare that element for printing since the only light portions to affect the element are the characters themselves, and all division lines and edges will be merged in with the dark portions.

The sensitized element may be on a zinc plate or the like so that the plate may be etched and prepared for use; or for a small number of impressions a collotype may be prepared by photographing directly in sensitized gelatine.

An apparatus for producing a surface to be photographed is shown in the accompanying drawings, in which—

Fig. 1 is a perspective view of the apparatus;

Fig. 2 is a top view of a character;

Fig. 3 is a side view of a character;

Fig. 4 is an elevation of a spacer.

Fig. 5 is a section on line 5—5 of Fig. 1; and

Fig. 6 is an illustration showing several features of the invention.

The apparatus consists of a base or board 10 on which are mounted bars 11. Each of these bars may be movably secured to the board by a spring clip as 12 (Fig. 1); or by a screw 13 (Fig. 5) passing through an end 14 of the bar and through a slot 15 of the board to engage a nut 16 held to a groove 17 in the board. Elongation of the slot 15 permits adjustment of the bar. The bars are undercut as at 18, Fig. 1.

For use with the board separable characters 19 are provided as shown in Figs. 2 and 3. Each of these comprises a shank 20 with an extended upper plate 21 and flanges 22 at the lower end. The shanks fit between the bars and the flanges engage the undercut portions of the bars. The shank bar has grooves 23 which may be variously formed for use in a distributing machine.

The character is formed on the upper surface of the plate. The plate may be given any contour so that the characters will fit together as desired.

For positioning the characters, spacers 24 are provided. As shown in Fig. 5, they are formed with spring legs 25 which frictionally engage the bars and are preferably dark colored. They are made of various widths for justifying purposes.

Because the characters are photographed, it is not necessary to have them reversed as in ordinary type, but the characters are set up as in ordinary reading matter as shown

in part 26 of Fig. 6. If any illustration or formula or the like is to be inserted, blank bars or blocks are inserted, on which the illustration is delineated, as by drawing directly thereon, or if the illustration be already prepared, by pasting or otherwise securing a negative copy 27 of right size, showing white lines on dark ground. In addition to the characters, a design or tracery 28 interweaving the characters, may be drawn on the assembled characters before photographing.

10 The board may be made large enough so that several pages may be set up and photographed simultaneously. The resulting plate may be used as a single plate or divided into portions or pages.

15 The light colored characters make possible the direct photographing on the sensitized plate or gelatine to be used in printing, avoiding the preparation of a negative and the making of a positive therefrom. The use of a prism in front of the camera lens secures a reversal of the image on the plate, 20 when that is desired.

25 Matter of different size type, to be inserted, may be first set up and photographed. From this another photograph 29 of right size giving white characters on a black background is prepared, and pasted or otherwise secured in its proper place in the assembled 30 matter.

I claim,

35 1. A process of obtaining a printing element, which consists in assembling characters, inserting blanks on whose surfaces spe-

cial characters are delineated, and photographing the assembled characters for the production of a printing element.

2. A process of preparing a printing element, which consists in assembling characters and blanks for the reception of special matter, the whole assemblage constituting substantially a unit upon which additional matter may be placed, and recording said assemblage on the printing element.

3. A surface structure which consists of elements carrying characters and blank elements for the reception of special matter, the whole assemblage of elements constituting substantially a surface upon which additional matter may be placed.

4. A surface structure which consists of members and elements carrying characters spaced by the members, the members also forming a connecting means between the characters so as to present a substantially unified appearance.

5. An apparatus for use in obtaining a printing element having in combination, 60 separable characters, a member, and bars mounted on the member for holding the characters, said characters having flat surfaces overlying the bars.

6. An apparatus for use in obtaining a printing element having in combination separable characters, a member, and bars adjustably mounted on the member for holding the characters whereby the spacing may be altered.

In testimony whereof I affix my signature.
JOSEPH N. NIELSEN.
